UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

STOVE LEG.

Application filed September 17, 1920. Serial No. 410,857.

To all whom it may concern:

Be it known that I, RUDOLPH HOFFMAN, a citizen of the United States, residing at Kankakee, in the county of Kankakee and 5 State of Illinois, have invented certain new and useful Improvements in Stove Legs, of which the following is a specification.

The invention relates in general to stoves, such as gas or oil cook stoves, and its aim 10 is directed more particularly to an improved manner of constructing the legs of the stove from sheet metal.

Stove legs have in the past been commonly constructed from a single piece of 15 metal of angular formation and shaped at the upper end to provide shoulders upon which may rest the portions of the stove superstructure. This method of construction has been relatively expensive and the 20 proper and accurate shaping of the upper end of the leg to provide the supporting shoulders has been accomplished only with considerable difficulty.

The object of my invention is to overcome 25 the objections to the former construction, and this object is attained by constructing the leg from separate pieces of sheet metal in a novel and advantageous manner which will be apparent as the description 30 proceeds.

A further object of the invention is to provide a stove leg of sheet metal construction and yet of a strong and rugged character.

In the accompanying drawings wherein I have illustrated a preferred form of the invention, Figure 1 is a fragmentary perspective view of a stove having supporting legs constructed in accordance with my invention. Fig. 2 is a fragmentary elevation of the improved leg with the portions of the stove superstructure which are secured thereto shown in section. Fig. 3 is a fragmentary perspective view of the 40 stove leg, showing particularly the stiffening means therefor. Fig. 4 is a perspective view of the upper portion of the leg attached. Fig. 5 is a plan view of the completed leg detached from the stove. Fig. 6 is a 45 plan view of the blank from which the lower or main portion of the leg is formed. Fig. 7 is a cross sectional view of the lower portion of the leg. Fig. 8 is a fragmentary vertical sectional view through the ex- 50

treme lower end of the leg showing the 55 construction of the foot portion therefor.

In the drawings, 7 designates generally the lower or base portion of the stove leg having secured at its upper end a top portion or shoe 8 in such relation as to provide 60 annular shoulders upon which the depending portions of the stove superstructure may rest as will be more fully explained hereinafter.

The lower or main portion 7 of the leg 65 is formed from a single sheet of metal of sufficiently heavy gauge, cut to provide a blank such, for example, as that shown in Fig. 6. Said blank is bent along a central longitudinal line into angular form to provide the side portions or walls 9 and 9^a of the leg; and the upper end of the blank is shaped to provide two substantially triangular portions 10 and 10^a bent upon transverse lines near the upper end of the blank 70 75 into substantially right-angular relation with reference to the side portions 9 and 9^a. When the triangular portions 10 and 10^a are thus bent into a substantially horizontal position, the adjacent edges thereof 80 abut as shown in Fig. 3 and may be secured together as by welding. The two portions 10 and 10^a when thus secured together constitute a rigid top plate for the lower or base portion of the leg. 85

The upper portion or supporting shoe 8 of the leg (Fig. 4) is formed from a sheet of metal separate from that of the blank from which the lower portion is formed, and comprises a plate 12 of a shape generally similar to that of the top plate 10, 10^a and having at its outer edges upturned flanges 13 and 13^a and at its rear or inner edge an upturned flange 14 carrying a horizontally disposed lug 15. Suitable apertures 16 are provided in the top plate 10, 10^a, and in the plate 12 of the upper portion 8, through which apertures are entered rivets 18 by which the two portions of the leg may be rigidly secured together. The plate 12 90 95 100 when thus secured upon the top plate 10, 10^a serves to further secure the portions of the top plate and hence the side portions or walls 9 and 9^a in fixed relationship.

In thus securing the supporting shoe 8 105 upon the lower or base portion 7 of the leg, the parts are relatively positioned so that the upstanding flanges 13 and 13^a coact with

the inturned flanges constituting the top plate 10, 10^a, to provide shoulders 19 (Fig. 2). That is to say, the shoe 8 is secured in position upon the top plate 10, 10^a with the flanges 13 and 13^a offset inwardly from the side portions 9 and 9^a of the leg base. Upon these shoulders 19 rest the depending edge portions of the bottom of the stove superstructure as shown in Fig. 2. Thus the 10 stove bottom 20 is shown as having a depending flange 21 reinforced by an angular strip 22 secured upon the under side of the bottom 20 by means of rivets 23. A securing band 24 is secured upon the outer side of the 15 depending flange 21 and to the upstanding flanges 13 and 13^a of the shoe 8 as by means of rivets 25, the latter extending also through the reinforcing strip 22 and thus rigidly securing the several parts together.

20 The horizontally disposed lug 15 at the rear portion of the supporting shoe 8 is adapted to engage with the under side of the bottom 20 of the stove, and is rigidly secured to the bottom by means of a rivet 25.

26.

For the purpose of strengthening the lower portion of the leg, I employ a member 27 secured within and bridging the angle. This member preferably extends substantially throughout the length of the lower portion 7 and for securing it in position, has opposite edge flanges 28 which may be spot welded or otherwise secured to the walls of the angle. It will be seen that this member 30 serves to tie the side portions or walls 9 and 9^a together throughout the length of the leg and especially the lower portion thereof, and also tends to stiffen the leg.

At their lower ends, the legs may be provided with feet 29 which as herein shown, are formed separate from the leg proper. Thus, it consists of a strip of metal bent to form a main fold 30 and an inner fold 31 and the lower end of the leg is inserted within the main fold and when the folds are compressed the foot portion is formed with five thicknesses or layers of metal. These layers are finally secured together as by soldering or welding. The obvious advantage in this 50 construction is that the lower end of the legs will not injure the floor or floor covering.

It will be apparent that I have provided a novel and advantageous construction for 55 stove legs enabling their manufacture at a relatively low cost and at the same time providing a construction of a very practical character adapted to support the stove superstructure in a thoroughly efficient and 60 practical manner. It is, of course, to be understood that the invention is not limited to details of construction herein shown and described in connection with the embodiment of the invention selected for purposes 65 of illustration, and especially is not limited

to the particular arrangement of the parts of the stove or the superstructure to which the leg is secured. Obviously, however, the shoulders 19 upon which the portions of the superstructure rest may be made of any 70 desired width by properly positioning the supporting shoe 8 with reference to the top plate 10, 10^a of the lower or base portion 7.

This application is a continuation in part 75 of my copending application, Serial No. 395,487, filed July 12, 1920.

I claim as my invention:

1. In a stove, the combination with a superstructure having a bottom with depending edge portions, a stove leg comprising 80 a main or base portion formed from a blank of sheet metal and having a rigid top plate, and an upper portion secured to said top plate and having upright flanges offset inwardly from the outer faces of the 85 base portion so as to form with said top plate shoulders upon which said edge portions of the stove are adapted to rest, said edge portions being rigidly secured to said flanges.

2. In a stove, the combination with a superstructure having depending edge portions, a leg formed from sheet metal and comprising a lower or base portion having 95 a top plate and an upper or supporting shoe offset inwardly upon and rigidly secured to said top plate and forming therewith shoulders upon which the depending edge portions of the superstructure are adapted 100 to rest, said shoe also having an upstanding portion to which the bottom plate of the superstructure is adapted to be secured.

3. A stove leg comprising a lower or base portion formed from a blank of metal bent into angular shape and providing a top 105 plate rigid therewith, and an upper portion rigidly secured to said top plate and inwardly offset so as to form therewith supporting shoulders upon which portions of the stove superstructure are adapted to rest. 110

4. A stove leg comprising a lower or base portion formed from a blank of metal bent to provide a top plate rigid therewith, and an upper portion adapted to be rigidly secured to said top plate and coacting 115 therewith to provide supporting shoulders upon which portions of the stove superstructure are adapted to rest, said upper portion having upright flanges rising from said shoulders to which the superstructure 120 may be secured.

5. In a stove, the combination of a bottom having a depending flange, a supporting leg comprising a base portion, and an upper portion formed separately from and 125 rigidly secured to the base portion, said upper portion providing a flange to which the bottom flange may be secured, and a second flange secured directly to said stove bottom.

6. A stove leg constructed from sheet metal and comprising a main or base portion bent into angular form to provide side walls each formed at its upper end with an enlargement having at its free end a triangular portion bent into perpendicular relation with respect to the side walls and secured together at their abutting edges to provide a top plate for the base portion, 10 means carried by said top plate whereby the leg may be secured to a depending part of the stove frame, and a reinforcing member for the leg bridging the angle formed by the side portions and having edge flanges 15 welded to the inner surfaces of the side portions near the free edges thereof and extending upwardly upon the inner sides of the enlarged upper portions of said side walls.
- 20 7. In a stove, the combination of a super-structure having a bottom provided with a depending flange at its front and side edges, an angular reinforcing strip secured upon the under side of the bottom and engaging 25 with the inner side of said flange, a supporting leg having two adjoining walls each provided with a flange at its upper end, a member formed separately from said walls but rigid with reference thereto and having 30 means coacting with said flanges to provide shoulders, and means for securing said depending flange of the stove bottom and its reinforcing strip to the first mentioned means with the lower edge of the reinforcing strip resting upon said shoulders, said 35 securing means including a band surrounding the depending flange of the bottom, the lower edge of said band also engaging upon said shoulders.
8. A stove leg constructed of sheet metal 40 bent to form two walls disposed substantially at right angles to each other, a member having its opposite side edges secured respectively to the inner sides of the walls and extending from near the upper 45 end of the leg to a short distance from the lower end thereof, and a foot portion formed from a separate sheet of metal folded so as to receive the end of the leg below said strengthening member, said foot 50 portion being rigidly secured to the leg.
9. A stove leg constructed of sheet metal adapted to be secured at its upper end to a frame to be supported and having at its lower end a foot portion formed from a 55 strip of metal bent to provide a main fold adapted to receive the lower end of the leg and an inner fold located within said main fold whereby to impart thickness to the foot portion, the latter being made rigid 60 with the lower end of the leg.

In testimony whereof, I have hereunto set my hand.

RUDOLPH HOFFMAN.
